UNITED STATES PATENT OFFICE.

CHARLES H. NUMAN, OF NEW YORK, N. Y.

DESIGN FOR A COMBINED PEN RACK AND TRAY.

43,155.

Specification for Design.

Patented Oct. 15, 1912.

Application filed August 9, 1912. Serial No. 714,316. Term of patent 3½ years.

To all whom it may concern:

Be it known that I, CHARLES H. NUMAN, a citizen of the United States, residing at New York city, in the county and State of New York, have invented a new, original, and ornamental Design for a Combined Pen Rack and Tray, of which the following is a specification, reference being had to the accompanying drawings, forming a part thereof, and in which—

Figure 1 is a top view, Fig. 2 a front ele-

vation, and Fig. 3 an end view of a combined pen rack and tray embodying my design.

I claim:

The ornamental design for a combined pen rack and tray, as shown.

CHARLES H. NUMAN.

Witnesses:

HERMAN GUSTOW,
CHAS. C. GILL.
